LABORATORY BURNER

Carl S. Hornberger, Glen Ellyn, Ill., assignor to
 Central Scientific Company, a corporation of
 Illinois

Application December 21, 1931, Serial No. 582,248

3 Claims. (Cl. 158—111)

This invention relates to laboratory burners which term is intended to include the many types of portable burners that are commonly used in scientific laboratories.

5 Among the principal objects of the invention is to provide a base for such burners having unusual stability; that can be supported in an elevated position on a ring without employing the customary wire gauze; that can be tilted almost 90° from the horizontal while supported on a ring without any danger of its sliding off; that provides an enlarged mixing chamber for the gas and air; that has a gas jet passage designed to effect a minimum retardance of the velocity of the jet; and that is cheap to manufacture, durable, and simple in form.

Further and other objects and advantages of the invention will become apparent as the disclosure proceeds and the description is read in conjunction with the accompanying drawing, in which

Fig. 1 is a series of diagrammatic views illustrating the versatility of the novel burner base;

Fig. 2 is a perspective view showing a preferred form of the invention associated with a supporting ring, it being noted that the burner is firmly seated on the ring although the latter is tilted at a steep angle;

Fig. 3 is a transverse, sectional view taken 30 through the center of the burner;

Fig. 4 is a bottom plan view of the base, a supporting ring being shown in dotted lines;

Fig. 5 illustrates a modified base; and

Fig. 6 shows a modified form of burner tube.

35 Bunsen burners have been used for years in scientific laboratories as a source of heat. There is probably no laboratory in the country that is not equipped with one or more Bunsen burners.

To those familiar with laboratory routine, the 40 ordinary Bunsen burner has several distinct disadvantages. Like other laboratory burners, Bunsen burners are ordinarily provided with circular bases that furnish only a fair degree of stability. When it is desired to hold the burner 45 in an elevated position in order to heat a particular piece of apparatus, it is customary to set up a ring stand and set the burner on a piece of wire gauze placed over the ring.

If the particular heating job required to be 50 accomplished demands that the burner be held at an angle, it is necessary to clamp the burner in such position.

If the burner, whether it be a Bunsen burner or some other type, is merely seated upon a wire gauze placed over a ring, it often happens that

the accidental touching of the gas hose will cause the burner to fall from its support. This tendency is aggravated by the weight of the hose itself. One such experience while performing a laboratory experiment is sufficient to demonstrate 5 the need for a more stable burner base.

The present invention provides a base, suitably adapted to be used with any of the many types of laboratory burners, which is so constructed that it can be placed upon a ring or disk support and 10 will be firmly held thereon by gravity even though the support be tilted at an angle approaching ninety degrees.

In the preferred form of the invention, the base assumes an H-shape and comprises two parallel 15 bar like members or legs 10 and 11, integrally connected by a bridge 12. Adjacent each end of the legs 10 and 11 are depending feet 13, 14, 15 and 16, the inner surfaces of which are equidistant from the geometric center of the base. 20

A laterally extending hose nipple 17 projects horizontally from the center of the base and is preferably ribbed as at 18 to firmly grip the gas hose.

Rising from the center of the bridge is a boss 25 19 bored at 20 to receive the burner tube or stack 21. The bore ends abruptly at 22 to provide a seat for the tube.

An enlarged bore 23 is made from the bottom of the base in axial alinement with the burner tube. 30 The upper end of this bore is gradually tapered or filleted as at 24 to merge with the shoulder 22 of the upper bore.

Gas is introduced into the burner through a passage 25 bored into the hose nipple 17 which 35 communicates with the mixing chamber 26 (which comprises the bore 23) by an inclined restricted passage 27. It has been shown by experiment that the best results are obtained when the passage 27 is so inclined that it directs the 40 incoming gas through the upper portion of the mixing chamber 26 and strikes the tube 21 at the greatest possible obtuse angle. This is so because the velocity of the gas stream is reduced in proportion to the angle at which it strikes the tube 45 or opposing wall, so that if the angle of incidence is the greatest possible obtuse angle, there will be no appreciable reduction of velocity. In consequence, a hotter and more forceful flame may be secured. 50

The burner tube 21 may be longitudinally slit for a short distance as at 28 and then transversely slit for a fractional portion of its circumference as at 29 to provide the necessary resilience for inserting the tube in its socket. 55

The amount of air allowed to mix with the incoming fuel is controlled by an adjustable closure which may take the form of a lever 30 pivoted at one end to a boss 31 by a screw 32. The 5 particular shape of the lever shown in the drawing has the advantage of providing a better rate of admission of air when the lever is adjacent its closed position.

The base is preferably cast in iron or other 10 dense metal in order to give it relatively great mass. This fact in conjunction with the particular form of the base and its relatively low center of gravity gives unusual stability to the burner.

An inspection of the drawing will clearly indicate the manner in which this H-form of base 15 may be supported on a ring stand at various angles. Referring to Fig. 1 for example, there is shown a distilling flask being heated at its base by two burners and at its neck by a third burner.

20 This furnishes an apt illustration of the utility of the novel base of this invention. Quite often in distilling liquids, it is desirable to employ two burners for heating the liquid and it is impossible to place two ordinary Bunsen burners in 25 position to heat the liquid without clamping them in tilted position. With the improved base, however, they may be placed upon tilted rings in the desired position and will be held in place solely by gravity.

30 In the same illustration, it is often desirable to heat the neck of the distilling flask in order to prevent condensation taking place along the walls of the neck. It is almost essential that a burner be held at elevated and tilted position to 35 accomplish the necessary heating of the neck. The illustration in Fig. 1 shows how easily this particular job of heating may be accomplished by the present invention.

The three other diagrammatic illustrations in 40 Fig. 1 appearing on the right of the distilling apparatus show that it makes no difference whether the legs of the base are horizontal or vertical, or whether a solid disk is used in place of a customary ring.

45 It is obvious that the invention is not limited to an H-base. For example, a three-legged base, as shown in Fig. 5 may be used although it does not have the same degree of stability that the H-base possesses. Likewise the base may be cast in the form of an X or Z or any other shape 50 that would furnish the desired stability.

In practice, the burner bases are made in sizes corresponding to standard ring diameters. These range from one to seven inches, that is 55 one inch, two inches, three inches, etc.

In a central draft burner of the type herein disclosed, it has been found that the enlarged bore 23 which forms the mixing chamber 26 constitutes the difference between failure and 60 success when gas of 700 B. T. U.'s per cubic ft. and up is used.

The shoulder formed at the junction of the tube bore 20 and the enlarged bore 23 has the effect of preventing molten or gummy substances 65 which may form on the interior of the burner

tube, from flowing into or over the passage 27 to impede the flow of fuel.

It will be noted that the burner of this invention may be quickly cleaned or reconditioned 5 since all the parts are readily accessible. There is no passage which cannot be easily reached by merely removing the burner tube.

In Fig. 6, there is shown a modified form of burner tube in which the top is spun over at 33 to provide a somewhat constricted opening. The 10 purpose of this is to stabilize the flame, especially when high B. T. U. gas is being used, although it is not fully understood how the stabilization is actually accomplished. Apparently the inwardly directed walls of the tube set up eddy currents 15 producing a better admixture of fuel and air, but irrespective of theory, a more stable flame is secured.

It will be understood that the above specific 20 description of preferred and modified forms of the invention is for the purpose of disclosure only and is not intended to impose any undue limitations upon the scope of the appended claims.

What I claim, therefore, is:

25 1. A laboratory burner adapted to be supported in an elevated position on a ring, said burner having a base comprising two spaced parallel bar-like members joined at their mid-section by a bridge, the bottom faces of said members being substantially flat and coplanar, and supporting means on the base comprising depending feet on the bar-like members having supporting faces which are equidistant from the center of the bridge and are adapted to engage an edge of the ring and hold the burner in place when the ring is tilted from the horizontal.

30 2. A laboratory burner adapted to be supported in an elevated position on a ring, said burner having a base comprising two spaced parallel bar-like members joined at their mid-section by a bridge, said bridge having a vertical bore to receive a burner tube, a valve for regulating the admittance of air through the bottom of the bore, said bridge being raised above the plane 40 of the bottom of the bar-like members to afford ready admittance of air to the bore, the bottom faces of said members being substantially flat and coplanar, and supporting means on the base comprising depending feet on the bar-like members having supporting faces which are equidistant from the center of the bridge and are adapted to engage an edge of the ring and hold the burner in place when the ring is tilted from the horizontal.

35 3. A laboratory burner having an extended base having portions with flat coplanar bottom surfaces adapted to seat on the top surface of a supporting ring or disk, said portions having feet depending therefrom having side faces 45 equidistant from the center of the base and adapted to engage a side face of said ring or disk to hold the burner in place when the ring or disk is tilted from the horizontal.

CARL S. HORNBERGER. 55
